TAPE DISPENSER

Jean O. Reinecke, Chicago, Ill., assignor to Derby Sealers,
Incorporated, Ansonia, Conn., a corporation of Connecticut

Application April 13, 1959, Serial No. 55,490

Term of patent 14 years

(Cl. D74—1)

Fig. 1 is a side elevational view of a tape dispenser embodying my new design;

Fig. 2 is a top plan view thereof; and

Fig. 3 is a front elevational view.

The broken line illustration in Fig. 1 of a roll of tape is for illustrative purposes only.

I claim:

The ornamental design for a tape dispenser, substantially as shown and described.
